UNITED STATES PATENT OFFICE.

JOSEPH NEWTON, OF DRESDEN, ENGLAND.

BOOT OR SHOE.

SPECIFICATION forming part of Letters Patent No. 665,797, dated January 8, 1901.

Application filed September 26, 1898. Serial No. 691,946. (No model.)

To all whom it may concern:

Be it known that I, JOSEPH NEWTON, earth-
enware manufacturer, a subject of the Queen
of Great Britain, residing at 35 Belgrave road,
5 Dresden, in the county of Stafford, England,
have invented a certain new and useful Im-
proved Boot or Shoe, of which the following
is a specification.

This invention relates to boots, shoes, and
10 similar articles of foot wearing-apparel, and
has for its object to provide them with outer
sole and heel portions of rubber, gutta-percha,
or compositions thereof of a particular con-
struction. These outer rubber sole and heel
15 portions constitute the treads proper to the
boot or shoe and are fixed or fastened to the
ordinary leather sole and heel or to the leather
under sole and heel, so that they form rigid
parts therewith.

20 The purpose of this invention is to obtain
a non-absorbent tread which has very little
surface, so that a more even temperature and
greater resistance to cold and heat to the feet
of the wearer are obtained and a large increase
25 of comfort in walking. Moreover, boots and
shoes fitted with treads constructed according
to this invention are non-slipping in frosty
weather, non-conductors of electricity, and
noiseless of tread, the latter being of great
30 importance in hospitals and sick-rooms.

The invention will be described in connec-
tion with the annexed sheet of drawings, in
which an elevation of a shoe with a tread con-
structed in accordance to this invention is
3 shown in Figure 1, an under side plan of the
same in Fig. 2, and a transverse vertical section
in Fig. 3; taken on the dotted line F, Fig. 2.
Figs. 4, 5, and 6 show various forms of con-
struction and affixment.

40 The shoe a has fitted to its upper a^2 in the
ordinary manner a leather sole and heel $a^3 a^4$.
To the bottom of this leather sole and heel
are attached correspondingly-sized rubber
sole and heel portions $c c^2$ of a particular con-
45 struction, the said portions to constitute
treads. These rubber sole and heel portions
are constructed or molded with outstanding
boundary rib portions $c^3 c^4$ and with set-back
or hollowed-out middles c^5 and edges c^6 , so
50 that there is no part of the middles of the
rubber treads in contact with the ground in
walking, but a free and well-defined air pas-

sage or space. This construction of the rub-
ber treads—viz., boundary ribs and hollowed-
out middle parts—is of importance in a shoe 55
constructed according to this invention, as
also is the leather under sole and heel parts,
as without this combination the advantages
hereinbefore enumerated could not be ob-
tained. For instance, practical tests show 60
that leather is the healthiest material to be
in contact with the foot, and without its in-
tervention between the rubber treads and the
foot the comfort desired in walking could not
be obtained. Further, by hollowing out or 65
setting back the middle parts of the rubber
treads and having only a boundary contact
with the ground and an intervening rubber
webbing between the said boundary rib parts
and the leather under sole the shock due to an 70
uneven tread, as stepping upon a projecting
stone, &c., is taken and cushioned evenly along
the boot or shoe by means of this intervening
webbing.

In Fig. 4 the rubber heel-tread is shown of 75
a studded construction, the set-back portions
in this case only being at the extreme edges.
This construction of heel-tread may be used
with advantage in some instances, as the
heel part of the shoe is not so sensitive to the 80
foot of the wearer as the sole part. These
sole and heel rubber portions, with their out-
standing rib parts, are, as regards each por-
tion, molded in one piece in Figs. 1, 2, 3, and
4, and rigidly cemented to the outer surfaces 85
of the leather under sole and heel of the shoe.

In Fig. 5 is shown a section of a shoe in
which the leather of the undersole is cut away
at its middle a^8 for the reception of the rub-
ber sole portion or tread, the latter being 90
dovetailed into the said cut-away part and
held therein as a secondary affixing means by
nails or screws $f^3 f^4$. In this case the outer
rubber tread is easily renewable when worn,
as the same can be easily detached from the 95
dovetailed recess and another one substituted,
and this without any skilled assistance.

In Fig. 6 another method of fixing the rub-
ber tread c to the leather undersole is shown.
Metal plates $m m$ are in this case fitted around 100
the extreme boundary of the rubber tread, and
form the means, through suitable screws, for
securely clamping the rubber treads in posi-
tion. In this case the rubber tread need not

be cemented to the leather undersole; but the said clamping-plate may form a secondary means to the cementing for the tread's affixment.

5 Having now described my invention, what I claim, and desire to secure by Letters Patent, is—

1. A boot or shoe having a leather sole entirely covered from the shank to the toe by an elastic rubber sole c , formed integral with the unbroken, offstanding tread-rib c^3 extending continuously at a distance from and parallel with its edge, to provide the continuous surrounding marginal portion c^6 and intervening web c^5 , substantially as shown and described.

2. A boot or shoe having a tread-surface comprising an elastic rubber strip formed integral with an unbroken offstanding tread-rib extending continuously at a distance from and parallel with the edge of the strip to provide a continuous surrounding marginal portion and intervening web, substantially as shown and described.

25 3. A boot or shoe having tread-surfaces, the front or sole portion of which is entirely covered from the shank to the toe by an elastic rubber strip c , formed integral with the unbroken offstanding tread-rib c^3 , extending continuously at a distance from and parallel with its edge, to provide the continuous surrounding marginal portion c^6 and intervening web c^5 , and the rear or heel portion of said boot or shoe being covered with a rubber strip having an offstanding tread arranged at

a distance from and parallel with the edge of the heel to provide a surrounding marginal portion, substantially as described.

4. A boot or shoe having a tread-surface comprising a rubber strip formed with an integral unbroken offstanding tread-rib extending continuously at a distance from and parallel with the edge of the strip to provide a continuous surrounding marginal portion and intervening web, and means engaging said marginal portion throughout the boundary edge thereof and constituting the means for securely clamping said tread-surface in position, substantially as described.

5. A boot or shoe having a tread thereof hollowed out and provided with undercut sides, and a tread-surface comprising a rubber strip formed with an integral unbroken offstanding tread-rib extending continuously at a distance from and parallel with the edge of the strip to provide a continuous surrounding marginal portion and intervening web, said marginal portion having dovetailed sides which fit into the said undercut sides of the hollowed-out tread to retain the said rubber tread-surface in position, substantially as described.

In testimony whereof I have signed my name to this specification in the presence of two subscribing witnesses.

JOSEPH NEWTON.
